[57] **CLAIM**

I claim the ornamental design for the article a lock for a container door, as shown and described.

DESCRIPTION

FIG. 1 is a top plan view of a lock for a container door showing my new design;

FIG. 2 is a front elevational view thereof;

FIG. 3 is a rear elevational view thereof;

FIG. 4 is a horizontal cross-sectional view thereof, taken along line 4—4 of FIG. 2;

FIG. 5 is a right side elevational view thereof;

FIG. 6 is a left side elevational view thereof;

FIG. 7 is a top, front, and right side perspective view thereof;

FIG. 8 is an exploded top, front, and right side perspective view thereof;

FIG. 9 is a top, rear, and right side perspective view thereof;

FIG. 10 is an exploded top, rear, and right side perspective view thereof;

FIG. 11 is a bottom plan view thereof;

FIG. 12 is a greatly reduced top, front, and right side perspective view thereof, showing the lock mounted on a container door, the broken-line disclosure of which is for illustrative purposes only and forms no part of the claimed design; and,

FIG. 13 is a reduced, exploded top, front, and right side perspective view thereof, showing the lock positioned relative to a handle, handle fitting and locking rod, the broken-line disclosures of which are for illustrative purposes only and form no part of the claimed design.
